UNITED STATES PATENT OFFICE.

VERNON E. CROSBY, OF MINNEAPOLIS, MINNESOTA.

REAR-SEAT WINDSHIELD.

1,405,499.

Specification of Letters Patent. Patented Feb. 7, 1922.

Application filed February 26, 1921. Serial No. 448,015.

To all whom it may concern:

Be it known that I, VERNON E. CROSBY, a citizen of the United States, residing at Minneapolis, in the county of Hennepin and State of Minnesota, have invented certain new and useful Improvements in Rear-Seat Windshields, of which the following is a specification.

My invention relates to rear seat windshields for automobiles. An object is to provide a shield of this character which can be easily and expeditiously secured in place for service when desired to protect the occupants of the rear seat from wind and rain, and which can be quickly swung up out of the way so as to be practically invisible when it is not desired to use the same. Another object is to provide a device of this character which is adjustable so as to fit automobiles of different makes and which can be readily applied to different cars without making any change in the usual construction thereof. Another object is to provide a device of this character which can be folded into a small space to make a compact package for shipment.

The full objects and advantages of my invention will appear in connection with the detailed description thereof and the novel features embodied in my inventive idea will be particularly pointed out in the claims.

In the accompanying drawings, which illustrate the application of my invention in one form,—

Fig. 1 is a view in longitudinal section of a portion of an automobile with my device applied thereto. Fig. 2 is a fragmentary view showing the manner of securing one of the side extensions of the wind-shield.

Fig. 3 is a view in section on the line 3—3 of Fig. 2. Fig. 4 is a view in section on the line 4—4 of Fig. 3. Fig. 5 is a view in section on the line 5—5 of Fig. 1. Fig. 6 is a view in cross-section through the automobile body showing my wind-shield construction in extended position. Fig. 7 is a sectional elevational view with portions broken away showing a telescoping tube which I employ.

Fig. 8 is a view in section on the line 8—8 of Fig. 9. Fig. 9 is a sectional elevational view of my spring-supporting device at right angles to the position shown in Fig. 8, and with the spring in substantially the position it occupies when the shield is in position for service.

Referring to the particular construction

shown in the drawings, numeral 10 designates the back portion of the front seat of an automobile, the latter being shown provided with the customary front wind-shield 60 12, the top or canopy 14 and the bow member 16. My rear-seat wind-shield comprises a curtain made up of pieces of flexible material such as fabricoid which is put together in double thickness, stitched together back to 65 back so that the curtain has a finished appearance on both sides. The top piece 18 of the curtain extends longitudinally and is sewed together to form a loop 20 as shown in Figs. 1 and 6. The top piece 18 and the 70 bottom piece 22 are connected by intermediate vertical strips 24 whereby openings are provided to receive panels 26 of transparent material such as celluloid. The top and bottom pieces are also connected by end 75 strips 28 to form side extensions containing transparent panels 30. The loop 20 is adapted to receive a rod or tube made up of end members 32 which telescope with a central member 34. The outer ends of the 80 tubes 32 are provided with holes 36 which are adapted to receive the ends portions 38 of substantially U-shaped springs having arms 40 and 42 connected by the curved portion 44. A pair of these springs are supported from the bow member 16 at each side of the car by clamps constructed as shown in Figs. 8 and 9. Each of these clamps has cooperating jaw members 46 and 48 the free ends of which are concaved in order that 90 they may be clamped upon the bow member 16. The jaw member 48 at its rear end is cut out at the middle thereof and provided with two end eyes 50, while the rear end of the jaw member 46 is provided at its middle 95 with an eye 52 adapted to fit between the eyes 50 and register therewith. The spring member 42 passes through these registering eyes in the manner of a pintle of a hinge, and the end of the member 42 has a head 54 100 which prevents the hinge from coming apart. A bolt 56 passing through the jaw members and provided with a wing nut 58 serves to clamp the jaws upon the bow member 16 and at the same time it clamps the 105 eyes 50 and 52 upon the spring member 42 so as to securely hold the latter. When the nut 58 is loosened the spring member 42 may be slid for adjusting the position of the spring relatively to the clamp. This permits the clamp to be positioned at a suitable place 110 on the bow member and then by adjusting

the spring the curtain supported by the telescopic tube may be brought directly over the back of the front seat, as shown in Fig. 1 regardless of the type of car. The curtain 5 is provided with suitable devices 60 for securing it to the back of the front seat, and when thus secured the resiliency of the two U-shaped springs keeps the curtain taut and when the curtain is released the springs 10 tend to bring the telescopic tube further up toward the top of the car, and by swinging the curtain upon the rod it may be secured in upward position by means of ears having button-holes 62 adapted to fit over buttons 15 64 placed at a suitable position in the top of the car, as upon one of the supporting bows of the canopy. The end portions of the top piece of fabric 18 are cut on an incline, as indicated at 66 to provide clearance for 20 bending the side extensions backwardly. When the side extensions are turned backwardly from the position shown in Fig. 6 to that shown in Fig. 1 they may be secured in this latter position in suitable manner, as 25 by clips 68 secured to the upper corners of the side extensions, and adapted to clasp the canopy 14.

The operation and advantages of my wind-shield construction will be readily understood from the foregoing description.

Fig. 1 shows the device secured in place for service, the end extensions having been bent backwardly from the position shown in Fig. 6 and secured by clips 68 and the bottom of the curtain having been secured to the back of the front seat by means of the fasteners 60. When it is not desired to use the wind-shield the clips 68 and the fastening devices 60 are unfastened and the side 35 extensions folded over upon the central portion of the curtain. The curtain is then held only by the telescopic tube and may be swung backwardly and secured to the top as indicated in dotted lines in Fig. 1, 40 where it will be entirely out of the way. The wind-shield may thus be easily and expeditiously secured in place for service or put up out of the way by the occupants 45 of the rear seat without the necessity of getting out in the mud and rain. The telescopic tube 32, 34 provides for variations in the width of the car and enables the device to be readily packed in a box, since 50 this tube may be detached from the curtain and taken apart. Furthermore, the flexibility of the U-shaped springs and their adjustability with relation to the clamps adapts the device for attachment to different 55 styles of cars.

60 I claim:

1. A rear-seat wind-shield for vehicles comprising a curtain, a rod upon which the top of said curtain is swingingly supported, a pair of U-shaped springs, means for securing one of the arms of said springs at

the sides of the vehicle to a canopy bow member, and means for attaching the ends of said rod to the other arms of said spring, the bottom of said curtain being adapted to be secured to the rear of the front seat or 70 to be swung upwardly around said rod.

2. A rear-seat wind-shield for vehicles comprising a curtain, a rod upon which the top of said curtain is swingingly supported, a pair of U-shaped springs, clamps adapted 75 to be secured at the sides of the vehicle to a canopy bow member for adjustably securing one of the arms of said springs, and means for attaching the ends of said rod to the other arms of said spring, the bottom of said curtain being adapted to be secured to the rear of the front seat or to be 80 swung upwardly around said rod.

3. A rear-seat wind-shield for vehicles comprising a curtain, a rod upon which the 85 top of said curtain is swingingly supported, a pair of U-shaped springs, clamps adapted to be secured at the sides of the vehicle to a canopy bow member, the jaw members of each clamp having registering eyes at their 90 rear ends through which one of the arms of the cooperating U-spring extends and constitutes a pintle, and means for attaching the ends of said rod to the other arms of said springs, the bottom of said curtain being adapted to be secured to the rear of the front seat or to be 95 swung upwardly around said rod.

4. A rear-seat wind-shield for vehicles comprising a curtain, a rod upon which 100 the top of said curtain is swingingly supported, a pair of U-shaped springs, clamps adapted to be secured at the sides of the vehicle to a canopy bow member, the jaw members of each clamp having registering 105 eyes at their rear ends through which one of the arms of the cooperating U-spring extends slidably and constitutes a pintle, means for drawing said jaw members together to simultaneously clamp them on the bow member and to clamp said spring arm in 110 adjusted position, and means for attaching the ends of said rod to the other arms of said springs, the bottom of said curtain being adapted to be secured to the rear of 115 the front seat or to be swung upwardly around said rod.

5. A rear-seat wind-shield for vehicles comprising a curtain, a rod upon which the top of said curtain is swingingly supported, 120 a pair of U-shaped springs, clamps adapted to be secured at the sides of the vehicle to a canopy bow member, the jaw members of each clamp having registering eyes at their 125 rear ends through which one of the arms of the cooperating U-spring extends slidably and constitutes a pintle, means for drawing said jaw members together to simultaneously clamp them on the bow member and to clamp said spring arm in adjustable 130 position.

tion, and offset end members on the other arms of said springs adapted to extend through holes in the ends of said rod, the bottom of said curtain being adapted to be secured to the rear of the front seat or to be swung upwardly around said rod.

6. A rear-seat wind-shield for vehicles comprising a curtain, a rod upon which the top of said curtain is swingingly supported, 10 a pair of springs adapted to be attached at the sides of the vehicle to a canopy bow member, means for attaching the ends of said

rod to the free ends of said springs, extensions at the sides of said curtain adapted to be folded upon the main portion of the 15 curtain, said extensions being cut on an incline at the top to provide clearance, and clips attached to said inclined portions for securing the extensions to the vehicle canopy in rearward position.

20 In testimony whereof I hereunto affix my signature.

VERNON E. CROSBY.
